Elihu Smith, of Albany, N.Y.
Letters Patent No. 583. Dated July 26th

The schedule referred to in these Letters Patent and making part of the same

To whom it may concern:

Be it known that I, Elihu Smith, of the city of Albany, State of New York, have produced a new Ornamental Design for the plates of a parlor stove, (which Stove I call Illuminator Parlor Stove,) and I declare that the annexed Drawings are full and accurate delineations of the ornamental plates, the portions of plates not shewn in the drawings, being symmetrically similar to the portions represented therein.

What I claim as my production and desire to secure by Letters Patent, is the combination and arrangement of Ornamental figures and forms represented in the accompanying drawings forming together an ornamental design for a parlor stove.
